UNITED STATES PATENT OFFICE.

GEORGE A. MELLON, OF ST. LOUIS, MISSOURI, ASSIGNOR TO PETER H. MELLON, OF ST. LOUIS, MISSOURI.

METALLIC FOLDING BED.

SPECIFICATION forming part of Letters Patent No. 759,538, dated May 10, 1904.

Application filed February 8, 1904. Serial No. 192,632. (No model.)

To all whom it may concern:

Be it known that I, GEORGE A. MELLON, a citizen of the United States, residing in the city of St. Louis, in the State of Missouri, have 5 invented certain new and useful Improvements in Metallic Folding Beds, of which the following is a full, clear, and exact description, reference being had to the accompanying drawings, forming part of this specification.

10 My invention relates to a bedstead having a bed-bottom designed to be lowered into horizontal position and raised into upright folded position, the present invention being in the nature of an improvement on the bedstead 15 shown in Letters Patent No. 537,424, issued April 9, 1895, to Peter H. Mellon, and referring more particularly to the counterbalance-weights by which the bed-bottom is upheld in its folded position and means by which the 20 head-piece connected to said weights is guided.

The invention consists in features of novelty hereinafter fully described, and pointed out in the claims.

Figure I is a perspective view of the head 25 portion of my bed. Fig. II is an enlarged perspective view of one of the counterbalance-weights. Fig. III is an enlarged section taken through one of the counterbalance-weights and illustrating the means for attaching it to the 30 head-rail of the bed-bottom. Fig. IV is a detail view of the bosses on the lower end of the web.

1 designates the head-posts of the bed, which are united by an upper tie-rod 2 and a lower 35 tie-rod 3. The head-posts are provided with legs 4, united by a connecting-rod 5.

6 designates brace-legs extending forwardly from the head-post legs and united to each other by a connecting-rod 7 and to the head- 40 post legs by connecting-rod 8.

9 designates guide-rods having their upper ends secured to the head-posts 1 and their lower ends secured to the lower tie-rod 3, so that they are spaced apart from the head- 45 posts. By connecting these guide-rods to the head-posts and tie-rod in the manner stated I provide the greatest stability for them, so that they are well braced and add to the strength of the head portion of the bed.

10 designates a skeleton head-piece that has 50 at its upper end a cross-rod 11, provided at its ends with forks 12, that are slidably fitted to the guide-rods 9. At the lower end of the head-piece is a cross-rod 13, that has projecting ends 14.

15 designates the side rails of the bed-bottom, which are swingingly united to the brace-legs 6 by swivels 16, located remote from the head ends of said rails.

17 is the head-rail of the bed-bottom, which 60 is of angle-iron and has a forwardly-projecting horizontal flange 18 and a downwardly-projecting vertical flange 19.

20 and 20' designate, respectively, two outer and an intermediate counterbalance-weight secured to the head-rail 17 to move therewith when the bed-bottom is raised and lowered. Each of the outer weights 20 is provided with an apertured ear 21, that receives one of the ends 14 of the lower head-piece cross-rod 14, 70 so that the weights will swivel on said rod. Each of the weights 20 and 20' is furnished at the forward side with a notch 22, that receives the bed-bottom head-rail, thereby providing a lower rear portion 23, that extends downwardly from the top of the head-rail against its vertical flange 19. At the center of each of the counterbalance-weights at its rear side is a pocket 24, between which and the opposite side of the weight is a web 25, that is provided with a vertical slot 26.

27 designates rivets that are seated in the vertical flange of the head-rail 17, which project rearwardly from said flange, as seen in Fig. III. On the rivets are washers 29, that 85 occupy positions in the pockets 24.

28 designates bosses projecting from the lower end of the web 25, as seen in Figs. II to IV, inclusive, and which face forwardly from said web. These bosses are designed to 90 engage beneath the lower edge of the vertical cross-rail flange 19 when the counterbalance-weights are in position on the cross-rail and in which position they serve to hold the weights from accidental displacement when 95 the bed-bottom is raised and lowered. It will be seen that the weights may be readily applied by inclining their upper portions slightly

forward in mounting them upon the head-rail and passing the legs 23, with their webs 25, downwardly, so that the rivets 27 will enter the slots 26, and when the weights are entirely lowered and seated the bosses 28 will engage the head-rail flange, as stated, to hold the weights in place. When the bed-bottom is moved into unfolded and folded positions, the counterbalance-weights travel therewith, and the head-piece connected to the weights 20 is caused to partake of a shifting movement in an upwardly and downwardly direction, as indicated by dotted lines, Fig. I, during which the forks 12 ride in engagement with the guide-
15 rods 9.

I claim as my invention—

1. In a folding bed, the combination with head-posts and brace-legs, of a bed-bottom swiveled to said brace-legs and having an angle-shaped head-rail, counterbalance-weights mounted on said head-rail, webs at the lower ends of said weights, and rivets passing through said head-rail and webs to secure the weights to said rail, substantially as set forth.
- 20 2. In a bed, the combination with head-posts and brace-legs extending therefrom, of a bed-

bottom swiveled to said brace-legs, an angle-shaped head-rail forming a part of said bed-bottom, and having horizontal and vertical flanges; notched counterbalance-weights resting on the horizontal flange of said head-rail and having legs bearing against the vertical flange of the rail, slotted webs in said weight-legs and rivets located in the head-rail vertical flange and passing through the slots in the 35 weight-webs, substantially as set forth.

3. In a folding bed, the combination with a bed-bottom having a head-rail, of rivets in said head-rail, notched counterbalance-weights seated on said head-rail and having their lower 40 ends arranged to straddle said rivets, and bosses projecting from said weights at their lower ends arranged to engage the lower edge of said head-rail, substantially as set forth.

In testimony whereof I have hereunto set 45 my hand, at the city of St. Louis, Missouri, this 4th day of February, 1904.

GEO. A. MELLON.

In presence of—

NELLIE V. ALEXANDER,
E. S. KNIGHT.
